SHOPPING BAG HANDLE

Irving A. Singer, Beechurst, N.Y., assignor to Standard International Corporation, Andover, Mass., a corporation of Ohio

Filed Mar. 21, 1969, Ser. No. 16,382

Term of patent 14 years

Int. Cl. D9—99

U.S. Cl. D9—192

FIG. 2

FIG. 1 is a side elevation of a shopping bag handle showing my new design, the side opposite being identical thereto; and

FIG. 2 is an end elevation thereof, the end opposite being identical thereto.

I claim:

The ornamental design for a shopping bag handle, substantially as shown and described.
